GEOGRAPHICAL CLOCK

Millard L. Beyer, Hempstead, N. Y.

Application November 15, 1950, Serial No. 195,867

7 Claims. (Cl. 58—43)

1

This invention relates to a clock, and more particularly to an illuminated novelty clock which in addition to indicating time accurately serves as an attractive ornament.

A feature of the invention is the provision of a simple and inexpensive clock structure which indicates time simultaneously of a number of different time zones.

Other features of the invention will be found in the following description given with the aid of the accompanying drawings, of which:

Fig. 1 is an elevational view of a clock according to a preferred embodiment of the present invention;

Fig. 2 is a vertical sectional view taken through Fig. 1;

Fig. 3 is a section taken through 3—3 of Fig. 2; and

Fig. 4 is a detail showing a detachable time zone indicator.

Referring now to the drawings, the clock comprises a base 10 preferably stamped from a single piece of non-tarnishable metal formed with a flat upper surface 11 and a turned over depending edge 12 which provides a support for the clock and a space underneath surface 11 for enclosing a conventional electrical clock motor 13 with its reduction gearing.

The clock motor 13 is enclosed preferably in a casing 14 formed with a flange 15 which is fastened coaxially to the under side of flat surface 11 by suitable screws or rivets.

The clock spindle 16 projects upwardly through a centrally located opening in surface 11. A disc 17 formed with a slightly inset flange or ridge on its upper surface is fastened to spindle 16 by any suitable means such as nut 19 which presses the disc against a shoulder 20 formed on spindle 16.

Disc 17 supports a hollow thin-walled cylinder 25 preferably formed from "Lucite" or other suitable transparent material, the edge of the cylinder resting on the portion of disc 17 extending beyond the flange. Cylinder 25, being quite light in weight, is secured to disc 17 by frictional engagement with flange 18 and, if desirable, by any further suitable means. From the foregoing it will be understood that disc 17 is driven by the clock motor 13 and the transparent cylinder 25 turns therewith. Preferably the gear train of the clock motor is such that the spindle 16 and the parts driven thereby make one revolution in twenty-four hours.

Four rods 26, 27, 28, and 29 are secured to the flat surface 11 of the base by nuts 30. These

2

rods preferably have a non-tarnishable surface, such as chrome, or they may be formed of a suitable stainless metal. Rods 27, 28, and 29 are tubular, while rod 26 is of much smaller cross section and solid. Rod 26 serves additionally as an indicator.

The rods 26—29 at their upper ends support a ring 33 immediately over the upper edge of the transparent cylinder 25 but clear of the same.

10 The upper ends of the rods extend through holes in ring 33 and are fastened thereto by nuts 34. A series of depending flaps 35 are punched out of ring 33 and extend into cylinder 25 immediately adjacent its inner surface but normally slightly spaced therefrom. The flaps protect the cylinder assembly by preventing any appreciable accidental displacement of the upper portion of the cylinder with respect to the rotary disc 17.

An electric light socket 38 is mounted on a 20 detachable plate in an opening formed in the center of ring 33 and a light bulb 39 depends therefrom into the interior of the transparent cylinder 25. The wires 40 and 41 for the light bulb are led from the external power circuit 42 at the base 25 through the bore of rods 29 and 27, respectively, which arrangement serves to conceal the wires.

The upper part of the structure is enclosed with a dome-like removable cover 45 preferably stamped from thin metal and formed with a depending edge closely fitting over the edge of disc 33 which frictionally holds the cover in place.

A plurality of spaced bands 46 may be printed or otherwise marked about the circumference of the transparent cylinder 25 and numbered to 35 indicate hours and marked with suitable graduations therebetween to show fractions thereof, the numerals of certain of the respective bands being offset circumferentially in accordance with the difference in time between time bands.

40 Time bands 46 may be printed on a transparent plastic tape which may be provided with a pressure sensitive adhesive on its under surface which makes it possible to install the time bands on the Lucite cylinder relatively offset as desired in accordance with different time zones.

Rod 26 is positioned along the mid-section of the front of the clock and serves as a time indicator in cooperation with the graduations on the bands 26. This rod may be made quite thin, having a diameter, say, of about one sixteenth of an inch. Rod 26 supports a plurality of name plates 50, one for each time band 46. The plates and rod may be formed as a single unit, for example, by casting or punching. In the enlarged detail structure shown in Fig. 4, the name plates 50 are

shown as being detachably secured to rod 26 by spring clips 51. It is intended that the name plates 50 shall carry on the front faces thereof the names of desired cities throughout the world, printed or applied thereto in any suitable manner, for which it is desired to indicate time. The name plates shown in Fig. 1 are too small to permit such printing in the drawing.

The device disclosed, in addition to being an attractive novelty, provides on a single cylinder an easily read indication of time in any desired group of time zones, and is of particular utility to radio amateurs and others interested in international communication.

What is claimed is:

1. In a clock of the character described, a base member, a clock motor supported thereby, a hollow transparent cylinder supported for rotation about a vertical axis by the clock motor; a plurality of vertical supporting members secured to the base in spaced relationship extending beyond the upper end of the cylinder, a flat ring overlying the top of the cylinder fastened to the upper portions of the supporting members, a lamp supported by the ring depending downward so as to illuminate the cylinder, and a cover member having a depending edge portion overlapping the edge of the ring.

2. In a clock of the character described, a base member, a clock motor supported thereby, a hollow transparent cylinder driven by the clock motor about a vertical axis and supported thereby, a plurality of independent bands of graduations disposed on the cylinder bearing time-indicating numerals relatively offset in accordance with different time zones; a common stationary vertical member serving as an indicator for the bands, a plurality of vertical rods secured to the base in spaced relationship extending beyond the upper end of the cylinder, a ring secured to the rods overlying the upper end of the cylinder, a lamp extending into the cylinder detachably supported by the ring, and a cover member enclosing the upper portion of the structure detachably secured to the ring.

3. In a clock of the character described, a base member, a clock motor supported thereby, a hollow transparent cylinder marked with a plurality of independent time scales relatively offset in accordance with different time zones driven about a vertical axis by the motor, a vertical rod secured to the base serving as a common reference for all scales, a plurality of additional vertical rods secured to the base in spaced relationship, a ring supported by the vertical rods overlying the top of the cylinder, and a cover member frictionally secured to the edge portion of the ring.

4. A combined clock and lamp structure comprising a base member, a clock motor supported thereby, a hollow transparent cylinder marked with a plurality of time scales relatively offset in accordance with different time zones, identifying markers for each zone, a vertical rod secured to the base for supporting the identifying markers and providing a common reference for all time scales, a plurality of additional vertical rods secured to the base in spaced relationship, a plate supported by the vertical rods overlying the top

of the cylinder, a lamp extending into the cylinder supported by the plate, and a cover for the structure having an edge portion formed to overlap the edge of the plate and frictionally engage the same.

5. A combined clock and lamp structure comprising a base member, a clock motor supported thereby, a hollow transparent cylinder marked with a plurality of time scales relatively offset in accordance with different time zones, identifying markers for each zone, a vertical rod secured to the base for supporting the identifying markers and providing a common reference for the various time scales, a plurality of hollow rods vertically secured to the base in spaced relationship, a plate supported by the hollow rods overlying the top of the cylinder, a lamp extending into the cylinder supported by the plate, potential circuits for the lamp extending from the base through one or more of the hollow rods, and a cover for the top of the structure having an edge portion formed to overlap the edge of the plate and frictionally engage the same.

6. In a clock of the character described, a base member, a clock motor supported thereby, a hollow transparent cylinder marked with a plurality of time scales relatively offset in accordance with different time zones driven about a vertical axis by the motor, a common reference for the scales comprising a rod secured to the base and disposed alongside the surface of the cylinder, a plurality of vertical rods secured to the base in spaced relationship, a ring supported by the vertical rods overlying the top of the cylinder, means depending from the ring for preventing accidental lateral displacement of the cylinder, and a cover member frictionally secured to the edge portion of the ring.

7. A combined clock and ornamental lamp comprising a base, a clock motor supported thereby, a hollow transparent cylinder marked with a plurality of time scales relatively offset in accordance with different time zones driven about a vertical axis by the motor, a common reference for the scales comprising a rod secured to the base and positioned alongside the surface of the cylinder, a plurality of vertical rods secured to the base, a ring supported thereby overlying the top of the cylinder, means depending from the ring for preventing accidental lateral displacement of the cylinder, a lamp supported by the ring extending downward into the interior of the cylinder, and a cover member detachably secured to the ring.

MILLARD L. BEYER.
